(57) **CLAIM**

The ornamental design for a food storage bag, as shown and described.

DESCRIPTION

FIG. 1 is a front elevational view of a food storage bag according to the present invention;

FIG. 2 is a right side elevational view of the food storage bag of FIG. 1;

FIG. 3 is a top-down view of the food storage bag of FIG. 1;

FIG. 4 is a front elevational view of the food storage bag of FIG. 1 with the latches and the bag open;

FIG. 5 is a right side elevational view of the food storage bag of FIG. 1 with the latches and the bag open;

FIG. 6 is another top-down view of the food storage bag of FIG. 1 with the latches and the bag open; and,

FIG. 7 is a front-right perspective view of the food storage bag of FIG. 1 with the latches and the bag open.

The broken lines showing indicia and structure in FIG. 5 and showing indicia in FIG. 7 are for the purpose of illustrating portions of the food storage bag and form no part of the claimed design.

1 Claim, 4 Drawing Sheets
